2 Sheets—Sheet 2.

F 75-4

Tid. 6.

A technical drawing of a curved metal component, likely a flange or a similar mechanical part. The component is shown in perspective, highlighting its curved profile. Several features are labeled with numbers:

- 19: Located at the top edge of the flange.
- 24: Located on the top edge of the flange, just below 19.
- 25: Located on the inner surface of the flange, near the bottom.
- 26: Located on the outer surface of the flange, below 25.
- 27: Located on the outer surface of the flange, below 26.
- 14: Located on the outer surface of the flange, near the top.
- 15: Located on the outer surface of the flange, near the bottom.

The drawing also includes a horizontal line with the text "Fig. 7." and a vertical line with the text "Fig. 8." on the left side.

UNITED STATES PATENT OFFICE.

WILLIS W. RUSSELL, OF AMSTERDAM, NEW YORK.

PRINTING-CYLINDER.

SPECIFICATION forming part of Letters Patent No. 655,802, dated August 14, 1900.

Application filed January 2, 1900. Serial No. 108. (No model.)

To all whom it may concern:

Be it known that I, WILLIS W. RUSSELL, a citizen of the United States, and a resident of Amsterdam, Montgomery county, State of New York, have invented a certain new and useful Printing-Cylinder; and I do declare that the following is a description thereof sufficiently clear, full, and exact to enable others skilled in the art to which it appertains to make and use the same, attention being called to the accompanying drawings, with the reference - numerals marked thereon, which form also a part of this specification.

This invention relates to printing-presses, and particularly to that part thereof which concerns the arrangement and adjustment of the printing face or form and the means whereby the same is held in position. It furthermore concerns only such printing faces or forms as are carried by printing-cylinders, around the surface of which they are disposed and to which they are secured, said printing-cylinders being rotated so as to bring successively all parts of their surface, being the printing-face, in contact with the paper passing between them and another cylindrical surface in the shape of a bed-roller or platen, whereby such paper receives the impression which the printing-cylinder transfers thereto. These printing faces or forms consist of sheets or plates of metal, like zinc, type-metal, stereotype - metal, electrotypes, &c., which plates carry the impression, engraved or otherwise imparted, and which are curved around the printing-cylinder and secured to the face thereof. In one construction as at present in use it is necessary that the printing-plate be so large as to reach entirely around the printing-cylinder in order to permit its ends to be secured to fixedly-located fastening devices, this irrespective of whether the actual size of the type or impression requires such a large expanse of plate or not. If any part of such a large printing-plate becomes damaged or loses its proper position by becoming stretched or warped, the whole must be removed, even if otherwise in good condition. If the thickness of a plate or the character of the metal is such as to lack sufficient elasticity or flexibility to permit its removal from the cylinder by opening and springing it off therefrom, such printing-cyl-

inder must be bodily removed from the press-frame to permit such sheet to be removed endwise, attachment or exchange of sheets under such conditions requiring, of course, the same procedure.

In multicolor-printing, where several printing-cylinders work in conjunction and supplementary to each other, each supplying only a portion or one color of the whole impression, perfect register and coincidence of the several colors separately printed are of prime necessity. This accuracy is only obtainable by means of a range of delicate adjustments, permitting variations and changes of positions to the most minute degree, not only of all of the printing-plates on one cylinder with reference to each other on the same cylinder, but also in multicolor-printing with reference to the printing-plates on the other cylinders, and, finally, also with reference to the working parts of the press and the impression - cylinder on which the material (paper) is carried.

To this end my invention comprises means whereby such printing-plates may be secured to a printing-cylinder, the construction being such that they may cover all or only a part of the surface of the printing-cylinder and do not have to be of such a size as to completely cover the entire circumference of the printing-cylinder. This feature of my attaching means enables me to cut up and subdivide the printing or type face in smaller portions, each of which portions may be independently attached or removed when change in position of any certain portion or entire removal of it is required on account of damage or for any other reason, which adjustment or removal of such limited portion may be accomplished without affecting the rest of the surface. These type-faces after being so subdivided enable me also to use heavier metal for them, since these separate portions or patches, covering circumferentially only a part of the cylinder-surface, do not have to be curved or bent around the entire cylinder when placed in position or removed. For such reason also, such pieces being placed simply against a particular part of the face of the cylinder, their attachment or removal may be accomplished with the cylinder in position and obviating the removal of the latter from the

press-frame to slip them off endwise or to spring them over the diameter of the cylinder. In addition to this feature of the fastening means, which permits universal and 5 independent attachment or removal of the type-forms as a whole or of any number of their component parts without disturbing the proper curve of the printing-plates, these means are, furthermore, of such a character 10 as to permit also adjustment longitudinally as well as circumferentially of each printing-plate without disturbing the others. The aforesaid adjustment being all local and affecting only the parts intended, it is not necessary to remove, change, or adjust any other 15 parts of the press.

In general, I may state that my invention is applicable wherever the printing is done from a rotary printing impression-cylinder 20 doing plain single or multi color work either on a sheet-rotary or a web-rotary printing-press.

In the following specification, and particularly pointed out in the claims at the end 25 thereof, is found a full description of my invention, together with its operation, parts, and construction, which latter is also illustrated in the accompanying drawings, in which—

30 Figure 1 is a perspective view of a printing-roller embodying one of the features of my invention. Fig. 2 is a vertical cross-section of the same. Fig. 3 is an end view illustrating another feature of my invention. These 35 two figures are double the size of Fig. 1. Fig. 4 is an enlarged edge view of one of the adjustable sections, showing the manner of connecting the flanged edge of the printing-plate thereto. Fig. 5 is a cross-section of Fig. 4. 40 Figs. 6 and 7 in views similar to the preceding ones show a modified construction of the features shown therein. Fig. 8 in a view similar to Fig. 2 shows a modified construction for connecting the printing-plate to the 45 adjustable sections of the printing-roller.

The printing-cylinders consist, first, of a core 11, provided with journals 12 at each end, which rest in bearings on the printing-press frame. (Not shown.) In a multicolor- 50 press a sufficient number of them are provided, all operating in conjunction with each other and with a rotary platen 13, all being positively rotated and all being adjustable with reference to each other and with reference 55 to the platen. The construction and arrangement of these parts, however, form no part of my invention. The surface or bed upon which the plate 14, carrying the impression, rests and to which it is attached 60 consists of a number of sections 15, all fitted against the face of the core and held thereon in a manner which leaves them free to be moved circumferentially. A preferable construction to so hold them is by screws 16, 65 which pass through them and enter blocks 17, occupying circumferential and undercut grooves 18. I propose to use by preference

not less than four sections, as shown in Figs. 1 and 2, which number may be increased, as shown in Figs. 3 and 8. The printing-plate 70 is flanged in the usual way, the flanges 19 being secured to the edges of sections 15, after which these latter are spread by means of a wedge 21, inserted between two of these sections, and whereby the printing-plate is 75 tightened. This wedge is held in place by means of a dovetail connection 22, its movement for adjusting, to tighten or loosen it, being by means of a screw 23.

In the form shown in Figs. 1 and 2 I use 80 four sections and two wedges diametrically opposite each other, these latter operating each in conjunction with two sections, one on each side of them. A roller so fitted out is particularly well adapted for use in connection with web rotary presses, having the additional advantage of not requiring a printing-plate of a size sufficient to entirely encircle the face of the roller, yet having the entire surface of it covered. The plates in this 90 case being each about half-circular may be conveniently placed, attached to, or removed from the side of the roller. As shown in Figs. 3 and 8, the sections are still more subdivided, there being a greater number of reduced 95 width operating in conjunction with one wedge interposed between two of them for the purpose of tightening the printing-plate. This form permits the use of plates of any length (circumferentially considered) and between extreme limits of course—that is, not larger than the circumference of the roller nor less than sufficient to reach from the section next to the wedge on one side to the first section on the other side. For these reasons 105 this form is best adapted for use in connection with sheet rotary presses.

For holding the printing-plates in position I provide dowel-pins 24 at the edge of the sections, which enter openings provided in the 110 flanges 19 of printing-plates 14. After being so engaged the sections are spread by means of the wedge, whereby the printing-plate is tightly held in position, as may be readily understood. The sections being held to the core 115 in the manner explained readily yield to the action of the wedge. Instead of using dowel-pins the printing-plate may be simply nailed or screwed to the face of the rollers—that is, to the sections thereat, as shown in Fig. 8—120 for which purpose preferably each second one is of wood or soft metal, like type-metal. In this case the printing-plates require no flanges.

Perfect adjustment or justification especially in multicolor printing is of course of foremost importance. Longitudinally—that is, circumferentially as to the printing-roller—I obtain it by the use of plates or washers 25, which may be of various thicknesses and are 130 inserted underneath the flanges 19 and between them and the edges of the sections, being carried on the dowel-pins. Laterally the adjustment is by having the dowel-pins mov-

able along the edge of the sections. For such purpose a base 26 is provided, upon which a number or only one dowel-pin is supported. I prefer to have each dowel-pin independently 5 mounted on its own base, as permitting a greater range of adjustment and also rendering this latter more convenient. Each of these bases is fitted into a groove 27 in the edges of sections 15 and provided with a slot 10 28, through which a screw 29 passes, entering a hole 31 in the bottom of groove 27, whereby the base, with its pin, is held in place, lateral adjustment being had to the extent of the length of slot 28. It is preferable 15 to provide these grooves 27 on both edges of each narrow section 15, thus permitting the attachment of dowel-pins on either side, as expediency may require. At the same time these grooves provide the necessary clearance 20 for the dowel-pins when the sections are close together. Instead of holding the dowel-pins in the manner described their bases might be dovetailed into groove 27, as shown in Figs. 6 and 7, and held by the end pressure of a 25 screw 32. Spacers or printers' leads 33 may be interposed between the different pins for their adjustment.

As will be seen, by the use of my invention it becomes unnecessary to use printing-plates 30 encircling the rollers entirely, thus obviating the objectionable necessity of engraving, for instance, larger plates than the subject would otherwise require. It further permits me to use a number of printing-plates side by side, 35 it being possible to connect each independently and at different points of the circumference of the roller by the provision I have made for such purpose. It finally permits me to adjust the printing-plates as a whole or 40 any part thereof independently, if in sections, either longitudinally—that is, circumferentially—or laterally, either at once in both directions or only in either one, thus satisfying all requirements which may be 45 made in this direction.

Having described my invention, I claim as new—

1. In a printing-roller the combination of a core, a number of comparatively-narrow surface-sections adjustably secured thereto to support the printing-plate, dowel-pins projecting from one of the edges of each section, to receive the perforated flanged edges of the printing-plate for the purpose of holding the

same in position, such attachment adapted 55 to be made between any two sections and at any point of the circumference of the roller, according to the length of the printing-plates and a wedge adapted to be inserted between two sections for the purpose of tightening 60 the sections between the edges of the printing-plates.

2. In a printing-roller, the combination of a core, circumferentially-adjustable surface-sections supported thereon, semicircular 65 printing-plates supported on these surface-sections, dowel-pins at their outer edges whereby the printing-plates are held in position and two wedges diametrically opposite each other and one each between the edges of one of the 70 semicircular printing-plates.

3. In a printing-roller the combination of a core, surface-sections fitted thereto upon which the printing-plate is to be supported and pins projecting from the edge of these 75 sections adapted to engage and hold the printing-plates in position, said pins being adjustably connected to the sections.

4. In a printing-roller, the combination of a core, surface-sections fitted thereto upon 80 which the printing-plate is to be supported, pins projecting from the edge of these sections adapted to engage and hold the printing-plates in position, said pins being each mounted upon a base, a groove in one edge of 85 each section into which these bases are fitted in a manner to be laterally adjustable in this groove and means to hold these bases in their adjusted position.

5. In a printing-roller, the combination of a 90 core, surface-sections fitted thereto upon which the printing-plate is to be supported, pins projecting from the edge of these sections adapted to engage and hold the printing-plates in position, said pins being each 95 mounted upon a base, a dovetailed groove into which these bases are fitted in a manner to be laterally movable therein, spacers to adjust the distance between them and a screw engaging them endwise to hold the entire row laterally in position.

In testimony whereof I hereunto set my hand in presence of two witnesses.

WILLIS W. RUSSELL.
